(57) **CLAIM**

The ornamental design for a trolley shopping cart as shown and described.

DESCRIPTION

FIG. 1 is a front, top and left side perspective view of a trolley shopping cart showing my new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the trolley shopping cart that form no part of the claimed design.
